UNITED STATES PATENT OFFICE

140,691

DESIGN FOR A BANDANA

Lawrence B. Jordan, Portland, Oreg.

Application February 5, 1945, Serial No. 117,764

Term of patent 3½ years

(Cl. D3—12)

To all whom it may concern:

Be it known that I, Lawrence B. Jordan, a citizen of the United States, residing at Portland, in the county of Multnomah and State of Oregon, have invented a new, original, and ornamental Design for a Bandana, of which the following is a specification, reference being had to the accompanying drawing, forming a part thereof.

The figure is a plan view of a bandana showing my new design.

I claim:

The ornamental design for a bandana, as shown.

LAWRENCE B. JORDAN.
